CLAIM

The ornamental design for a holder and clip, as shown and described.

DESCRIPTION

FIG. 1 is a front perspective view of a holder and clip;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a top perspective view thereof;

FIG. 8 is a bottom plan view thereof; and,

FIG. 9 is a bottom perspective view thereof.

The broken lines in the figures show portions of the holder and clip which form no part of the claimed design.
